UNITED STATES PATENT OFFICE.

JOSEPH PERCY REMINGTON, OF PHILADELPHIA, PENNSYLVANIA, ASSIGNOR TO REMINGTON MANUFACTURING COMPANY, INC., OF PHILADELPHIA, PENNSYLVANIA, A CORPORATION OF PENNSYLVANIA.

CAPSULE-FILLING MECHANISM.

No. 899,761.

Specification of Letters Patent. Patented Sept. 29, 1908.

Application filed February 7, 1908. Serial No. 414,706.

To all whom it may concern:

Be it known that I, JOSEPH PERCY REMINGTON, of Philadelphia, in the county of Philadelphia and State of Pennsylvania, 5 have invented certain new and useful Improvements in Capsule-Filling Mechanism, whereof the following is a specification, reference being had to the accompanying drawings.

10 My invention relates to a device whereby a plurality of two-piece capsules, such as are commonly used in medicine, may be simultaneously filled and closed.

Gelatin capsules as ordinarily used in 15 medicine, consist of two members, a cup, and a cap, which overlaps and closes the cup, and my invention comprises a cap-table for the reception and securing of the caps of a plurality of capsules, and a corresponding 20 cup-table registering with the cap-table and capable of simultaneously engaging the cups of the capsules whose caps are secured within the cap-table, whereby all of the cups may be simultaneously separated from their caps, 25 filled, compacted and closed by the proper manipulation of the two tables.

It is desirable to employ in connection with 30 my device means for automatically placing a plurality of capped capsules in their initial position in my apparatus, and also means for simultaneously ejecting the filled capsules from the apparatus. The former of these means forms the subject matter of a separate application, filed by me simultaneously herewith; and the latter of these means are 35 shown and described in connection with this application, but it will be understood that the capsule handling and filling mechanism may be employed separately from and irrespec- 40 tive of either or both the capsule placing apparatus, and the capsule ejecting apparatus.

In the accompanying drawings, Figure I, 45 is an elevation of a table embodying my invention, and adapted to receive the caps of one hundred capsules. Fig. II, is a central longitudinal section of the same showing capsules in position therein. Fig. III, is an elevation showing the cap-table inverted and placed with its capsules upon a cup-table, 50 which is adapted to receive the cup portion of the capsules. Fig. IV, is a central longitudinal section of the same. Fig. V, is a plan view of the same from above. Fig. VI, is a central longitudinal section of the tables assembled as before (but inverted), in combi- 55 nation with a compacting and ejecting device. Fig. VII, is a plan section taken on the line VII, VII, and looking in the direction of the arrows in Fig. VI.

The cap table is shown in elevation in Fig. I, with capsules *in situ* and may be first described. It comprises four parallel similarly perforated plates, namely, a surface plate 1, a slide plate 2, a backing plate 3, and a bottom plate 4. Each one of these four plates 60 is accurately perforated by a plurality of suitable perforations for accurately receiving the caps of capsules. For convenience these perforations should be arranged in lines, say ten lines of ten holes each, for one or more 65 lines may then be used to the exclusion of others so that only so many capsules may be filled as the operator may desire. The perforations of all four plates are in precise correspondence with each other. The surface 70 plate and the backing plate are in fixed relation to each other, separated by a small interval, with their perforations in exact alignment, being so maintained by four legs 5, 5, 5, 5, upon which the table is supported. The 75 surface plate is preferably somewhat longer than the others, as seen in Fig. II. Between the surface plate 1, and backing plate 3, is the slide plate 2, provided with perforations corresponding precisely with those of its 80 fellows, but capable of a slight lateral motion in relation to them, whereby a grip or bite may be placed upon the caps of all capsules resting within the perforations of the table. For 85 the purpose of controlling this sliding motion, the slide plate 2, is fitted with a shoulder 6, carrying a horizontal projecting pin 7, which passes through a lug 13, attached beneath the surface plate 1, and is pierced by a pivot 8, which unites the extremities of a yoke 95 piece 9, with a handle 10. The extremities of the yoke piece are formed with a cam surface 11, bearing against the lug 13, and so shaped in relation to the axis of the pivot 8, that when the yoke is swung into its horizontal 100 position the slide plate is drawn slightly toward the end of the table, in opposition to the compression of a spring 12, which is interposed between the lug 13, and the shoulder 6. When the yoke 9, hangs vertically as 105 shown in the drawings, the perforations of the slide plate 2, are in precise alignment with those of the plates 1, and 3, but when the yoke piece is raised to its horizontal position, the slide plate is sufficiently moved to bring 110

its perforations slightly out of alinement and therefore effect its grip upon the caps of the capsules resting within the perforations of the table. For purposes of adjustment the 5 pivot 8, is received within a horizontal slot 15, in the pin 7, with a collar 16, surrounding the pin and bearing against this pivot and capable of being driven further down the pin by the nut 17. In this way wear either upon 10 the circular perforations of the plate or of the cam surface 11, may be taken up as desired. The bottom plate 4, is mounted in sliding relation to the table, the legs 5, of the table passing through slots 19, in said plate, so 15 that it is capable of motion in the same direction as that of slide plate 2, but somewhat greater in extent. Normally the perforations of the bottom plate 4, are so far out of alinement with those of the other three as to 20 oppose to the centers of the latter perforations the partitions between the former. The bottom plate is maintained in this normal position by means of a spring 20, centered on posts 21, 22, attached one to the lug 25 13, and the other to a lug 25, fast to the bottom of said plate 4, but the bottom plate may, by pressure in opposition to said spring applied either manually or by the ejecting apparatus hereafter to be described, be thrown 30 to the other end of its play whereby the perforations of the plate 4, will be in alinement with those of the other three plates. The cup table is further provided with separating levers 30, 30, 30, 30, pivoted in opposing 35 pairs at the sides of the plate, each pair being united by a cross-rod 31. These separating levers have cam surfaces 35, so that when they are moved manually from the horizontal position in which they appear in Figs. I, 40 and II, they assist in effecting the separation of the cup table from the cap table. Said levers may normally be maintained in their horizontal position by the springs 32. When each carries a large number of capsule parts 45 in engagement considerable force may be required to separate them. The cup table is further provided as to its surface plate with four registering holes 33, 33, 33, 33, suitably placed and arranged so as to assist the registration not only of the cup table with the 50 cap table, but also of the ejecting apparatus and if desired of a capsule placing apparatus therewith. For the purpose of effecting the registration of the cup table with the cap table, the holes 33, are provided with raised collars 34, which are received within corresponding holes of the plate of the cap table. 55 The cup table is in most respects a duplication of the cap table, except that its apertures are of a somewhat smaller diameter required to accurately receive and hold the smaller cup portions of the capsules. It too comprises four plates, to wit, a surface plate 41, a slide plate 42, a backing plate 43, and a 60 bottom plate 44. The mechanism for effect-

ing the slide motion of the slide plate 42, is precisely similar to that employed in the cup table, and need not be again specifically described. It will be noted that the bottom plate 44, of the cup table is situated at a 70 greater distance below the surface of the table than is the case in the cap table, this difference being accounted for by the greater length of the cup portion of the ordinary capsule. The cup table is provided with no 75 separating levers. Its surface plate 41, is however, of greater width than that of the surface plate 1, of the cap table, this increased extent being useful for the purpose of facilitating the manipulation of the material with which it is proposed to fill the capsules, and also affording a surface against which the separating levers of the cap table bear.

It is convenient to employ in connection 85 with the parts thus described a compacting and ejecting device which I have shown in Fig. VI. This device consists of a plate 50, provided with the proper number of plungers 51, suitably attached thereto in position to 90 correspond to the perforations of the plates of the two tables. It is also provided with handles 52, and with registering studs 53, which, when the compacter is placed in proper juxtaposition to the cup table enter 95 the registering holes 33, by which the tables themselves are maintained in proper alinement. These studs are surrounded with sliding collars 54, and by coiled springs 55, interposed between the plate and the collar, 100 so that when the ejector is placed above the table in position for the studs to pass down through the registering holes 33, the collars resting on the surface plate of the table will cause the coiled spring to sustain the weight 105 of the ejector so that its plungers only descend through the apertures of the plates when sufficient manual pressure is exerted upon the ejector from above. The plate 50, is cut away along the lines 56, 56, in order to 110 accommodate the legs of whichever inverted table is uppermost and prevent them from interfering with the downward motion of the ejector. The ejecting apparatus is further provided with a depending key 60, having at 115 its lower edge two inclined cam surfaces 61, 62. This key is for purposes of safety and for the manipulation of the bottom plates 4, and 44. The bottom plate 4, has a projection 63, at one end provided with an aperture 120 65, having its inner edge adapted to co-act with the cam surface 62. The bottom plate 44, has a projection 66, at one end provided with a notch 67, having its inner edge adapted to co-act with cam surface 61. Surface 125 plates 1, and 41, are also provided with registering apertures 68, having their sides in line with the sides of aperture 65, and notch 67, and adapted to allow key 60, to pass therethrough. Ordinarily the bottom plates 130

4, and 44, by reason of the tension of their springs, are maintained out of alinement with the regular series of apertures of the table. This is the normal position during 5 the operation of the device, except when the ejecting device is to be used for capping the capsules or for ejecting purposes.

When about to cap the capsule it is important that the bottom plate 44, should 10 have its apertures in precise alinement with the other apertures of the two tables, and after the capsules are capped, the apertures in the bottom plate 4, should be put in precise alinement with the other apertures of the 15 two tables in order that said capsules may be ejected. This alinement may be effected manually, but as mistakes may thus be made, I have provided the devices just described by which when the ejector is drawn 20 down the cam surface 61, on the end of key 60, automatically pushes bottom plate 44, into alinement and the capsules are capped; and upon the further downward movement 25 of said ejector the cam surface 62, automatically pushes bottom plate 4, into alinement, thus allowing the capsules to be ejected.

I will now describe the operation of the parts hitherto identified:—At the beginning 30 of the operation of filling a number of capsules, the cap table is set upright on its legs, and within its apertures are placed as many capsules as are to be filled, care being taken that the cap portion, and not the cup portion, shall be lowermost resting upon the bottom 35 plate 4. The operation of thus inserting the capsules in position within the table may be performed manually, or it may be performed automatically by a special capsule-placing apparatus invented by me, and which forms 40 the subject matter of another application which I am filing simultaneously herewith. When the capsules are in place in the cap plate, as seen in Figs. I, and II, the handle 10, is elevated, moving the sliding plate 2, to a 45 sufficient extent to firmly grip every one of the caps and hold it within its seat in the table against any force which may be applied to remove the cup from the cap. The cap table is then inverted and placed upon the 50 cup table with registration of the apertures 33, 33, causing the cup of every capsule to enter its proper seat within the cup table. This combination is illustrated in Figs. III. and IV. The hand lever of the cup table is 55 then raised to horizontal position, thus moving the slide plate so as to grip all of the cups and hold them firmly within their seats in the cup table. The tables are now separated, which operation may be facilitated by using 60 the separating levers 30, and as a result of the separation, all of the cups will be separated from their caps each being held within the seats of their respective tables. The edges of the cups will project considerably above 65 the surface of the cup table, but by tempora-

rily loosening the grip of the slide plate 42, by its hand lever, they may all be manually depressed within their seats until they rest upon the bottom plate with their edges flush with the surface of the table, when the hand lever 70 is again moved to grip the cups in place. The filling of all the cups may now be performed either manually or by means of any well known filling apparatus by which an equal fractional charge of a given substance 75 may be placed within each one of the entire series of cups. If the filling substance is a powder it is often desirable to compact it within the cup, and for this purpose the ejector may be used by simply placing it 80 above the cup table and pressing it down momentarily with sufficient force to drive its plungers into the cups to effect the compaction. The cap table is now again placed in inverted position directly over the cup table 85 with its charged cups and the two, without changing their relative position, inverted so as to bring the cup table uppermost. It is now necessary to first drive each one of the filled cups down into its cap and then eject 90 the filled capsule. For this purpose the hand-levers of the cup table and cap table are turned to loosen the slide plates 2, and 95 42, and release each one of the cups and caps from its grip. The ejector is then placed in position over the combined tables, the entire apparatus as thus assembled being shown in Figs. VI, and VII. Moderate pressure upon the ejector in this position drives each one of the filled cups down into its cap, the requisite 100 movement of the bottom plate 44, being secured by the action of the depending cam surface 61, as it passes through the plate 44. The parts are shown in this position in Fig. VI. As soon as the capsules have thus had 105 their parts united, a further and stronger pressure is given to the ejector so that the cam surface 62, comes into contact with and moves the bottom plate 4, so as to bring its apertures into alinement with all of the apertures above it which contain the capsules. Under these circumstances, the filled capsules are wholly unsupported beneath and the further downward motion of the plungers drives them down and out of the apertures so 110 that they fall under the cap table, the entire operation being thus completed.

Having thus described my invention, I claim:—

1. In a capsule filling apparatus, the combination of a plurality of parallel and similarly perforated plates, the apertures of which are adapted to register, one of said plates normally having its apertures out of registry with those of said other plates and 120 acting as a support for one end of the capsules; and means for moving said plate to aline its apertures with those of said other plates.

2. In a capsule filling apparatus, the com- 130

5 combination of a plurality of parallel and similarly perforated plates with apertures adapted to receive capsule members; means for moving one of said plates out of alinement to grip the capsule members resting within the apertures; another similarly perforated plate normally having its apertures out of alinement with those of said plurality of plates and so placed in parallel relation thereto as 10 to act as a support for one end of the capsules; and means for moving said supporting plate to aline its apertures with those of said other plates.

15 3. In a capsule filling apparatus, the combination a perforated plate with apertures adapted to receive capsule members; another similarly perforated plate normally having its apertures out of alinement with the first mentioned plate and so placed in 20 parallel relation to it, that capsule members resting within the apertures of the first plate rest with their bottoms on the second mentioned plate, while their edges are flush with the surface of the first mentioned plate; and 25 means for moving the second mentioned plate so that its apertures are in alinement with those of the first mentioned plate, whereby the capsule members in the one may pass through the perforations of the other, 30 substantially as described.

35 4. In a capsule filling apparatus, the combination of a perforated plate with apertures adapted to receive capsule members; another similarly perforated plate normally having its apertures out of alinement with the first mentioned plate and so placed in 40 parallel relation to it, that capsule members resting within the apertures of the first plate rest with their bottoms on the second mentioned plate, while their edges are flush with the surface of the first mentioned plate; means for moving the second mentioned plate so that its apertures are in alinement with those of the first mentioned plate, 45 whereby the capsule members in the one may pass through the perforations of the other; an ejector with plungers corresponding to each one of the apertures of the plates; and means whereby as said plungers are passed through 50 the apertures of the plates both plates are automatically maintained in alinement so that capsules or plungers may pass through the apertures of both.

55 5. In a capsule filling apparatus, the combination of two tables each fitted with a plurality of parallel and similarly perforated plates, the apertures of which register and are adapted each to receive a capsule member; means for sliding one plate in each table 60 sufficiently out of alinement to grip the capsule members resting within the apertures; and means for supporting the ends of the capsule members when the grip on said members has been released,

6. In a capsule filling apparatus, the combination of two capsule plates with registering apertures adapted to receive the one the larger and the other the smaller of the members of a capsule; means for gripping the capsule members within their respective plates; and means for supporting the ends of both the capsule members when the grip thereon has been released.

7. In a capsule filling apparatus, the combination of two rectilinearly detachable capsule plates with registering apertures adapted to receive the one the larger and the other the smaller of the members of a capsule; means for gripping the capsule members within their respective plates; together with 80 a pair of levers for separating the two plates.

8. In a capsule filling apparatus the combination of two rectilinearly detachable capsule plates with registering apertures adapted to receive the one the larger and the other 85 the smaller of the members of a capsule; means for gripping the capsule members within their respective plates; and means for supporting the cap ends of said capsule members, together with means for ejecting from 90 the plates capsules formed by the combination of the capsule members contained within the corresponding apertures of the plates.

9. In a capsule filling apparatus, the combination of two rectilinearly detachable 95 tables each fitted with a plurality of parallel and similarly perforated plates, the apertures of which register, and are adapted each to receive a capsule member; means for sliding one plate in each table sufficiently out of 100 alinement to grip the capsule members resting within the apertures; means for separating the two tables; and means in each table for supporting the ends of the capsule members.

10. In a capsule filling apparatus, the combination of two tables each fitted with a plurality of parallel and similarly perforated plates, the apertures of which register and are adapted each to receive a capsule member; means for sliding one plate in each table 110 sufficiently out of alinement to grip the capsule members resting within the apertures; means for separating the two tables; and means for compacting the contents of the 115 separated capsule members in one of said tables.

11. In a capsule filling apparatus, the combination of two tables each fitted with a plurality of parallel and similarly perforated 120 plates, the apertures of which register and are adapted each to receive a capsule member; means for sliding one plate in each table sufficiently out of alinement to grip the capsule members resting within the apertures; 125 means for separating the two tables; and means adapted to compact the contents of either of the capsule members when said

tables are separated and to eject the filled capsules when the tables are together.

12. In a capsule filling apparatus, the combination of two tables each fitted with a plurality of parallel and similarly perforated plates, the apertures of which register and are adapted each to receive a capsule member; a bottom plate in each table similarly perforated as the first mentioned plates of its table, but normally having its apertures out of registry with those of said other plates; and means for moving first one and then the other of said bottom plates into alinement with said other plates.

13. In a capsule filling apparatus, the combination of two tables each fitted with a plurality of parallel and similarly perforated plates, the apertures of which register and are adapted each to receive a capsule member; a bottom plate in each table similarly perforated as the first mentioned plates of its table, but normally having its apertures out of registry with those of said other plates; and means comprising a key having two cam surfaces for engaging said bottom plates, whereby first one and then the other of said bottom plates may be brought into alinement with said other plates.

14. In a capsule filling apparatus, the combination of two tables each fitted with a plurality of parallel and similarly perforated plates, the apertures of which register and are adapted each to receive a capsule member, the surface plate of one of said tables being provided with a plurality of registering holes; and the surface plate of the other of said tables being provided with raised collars adapted to enter said registering holes; and an ejecting and packing device provided with posts for entering into said registering holes.

15. In a capsule filling apparatus, the combination of a table fitted with a plurality of parallel and similarly perforated plates, the apertures of which are adapted to register and each to receive a capsule member; means for supporting the ends of the capsule members; and means comprising entering plungers located corresponding to said apertures for compacting the contents of the capsule members held in said table.

16. In a capsule filling apparatus, the combination with a table provided with means for holding a number of capsule members, and means for supporting the ends of the capsule members; of a packing device arranged to be placed above said table, and comprising plungers corresponding in loca-

tion to that of said capsule members, to pack the contents of said members.

17. In a capsule filling apparatus, the combination of two tables each fitted with means for holding a number of capsule members and with means for supporting the ends of said members; a packing and ejecting device arranged to be placed above one of said tables to pack the contents of the capsule members held thereby, and to force the cap and cup members together when said tables are placed in juxtaposition and thereafter ejecting the capsules.

18. In a capsule filling apparatus, the combination of a table fitted with a plurality of parallel and similarly perforated plates, the apertures of which register and are adapted each to receive a capsule member, said table being fitted with supporting legs; another similarly perforated plate normally having its apertures out of alinement with those of said plates and provided with slots coacting with said legs for limiting the movement of said plate to bring its perforations into alinement with those of said parallel plates.

19. In a capsule filling apparatus, the combination of two tables each fitted with a plurality of parallel and similarly perforated plates, the apertures of which are adapted to register and receive a capsule member; a packing and ejecting device adapted to be placed above said tables and comprising a set of plungers located correspondingly to the apertures in said tables; and means for normally maintaining said plungers in raised position.

20. In a capsule filling apparatus, the combination of two tables, each fitted with a plurality of parallel and similarly perforated plates, the apertures of which are adapted to register and receive a capsule member; a packing and ejecting device adapted to be placed above said tables and comprising a set of plungers located correspondingly to the apertures in said tables; a plurality of supporting pins for said device adapted to enter corresponding perforations in the surface plates of said tables; and supporting springs surrounding said pins to normally maintain said plungers in raised position.

In testimony whereof, I have hereunto signed my name, at Philadelphia, Pennsylvania, this fifth day of February, 1908.

JOSEPH PERCY REMINGTON.
